[57] CLAIM

The ornamental design for a garden storage structure, as shown and described.

DESCRIPTION

FIG. 1 is a perspective view of a garden storage structure showing my new design;
FIG. 2 is a front elevational view thereof;
FIG. 3 is a rear elevational view thereof;
FIG. 4 is a side elevational view thereof, the opposite being a mere image thereof;
FIG. 5 is a top plan view thereof;
FIG. 6 is a bottom plan view thereof;
FIG. 7 is a perspective view of a second embodiment of a garden storage structure showing my new design;
FIG. 8 is a front elevational view of the garden storage structure depicted in FIG. 7;
FIG. 9 is a rear elevational view of the garden storage structure depicted in FIG. 7;
FIG. 10 is a side elevational view of the garden storage structure depicted in FIG. 7;
FIG. 11 is a top plan view of the garden storage structure depicted in FIG. 7; and,
FIG. 12 is a bottom plan view of the garden storage structure depicted in FIG. 7.
